UNITED STATES PATENT OFFICE.

WILLIAM K. HENRY, OF NEW BRITAIN, CONNECTICUT, ASSIGNOR TO P. & F. CORBIN, OF NEW BRITAIN, CONNECTICUT, A CORPORATION OF CONNECTICUT.

DOOR CLOSER AND CHECK.

No. 873,433.

Specification of Letters Patent.

Patented Dec. 10, 1907.

Application filed July 30, 1907. Serial No. 386,274.

To all whom it may concern:

Be it known that I, WILLIAM K. HENRY, a citizen of the United States, residing at New Britain, county of Hartford, State of Connecticut, have invented certain new and useful Improvements in Door Closers and Checks, of which the following is a full, clear, and exact description.

My invention relates to closers and checks for doors, and more particularly such as are located in the floor or door sill, to serve also to support the door.

The object of my invention is to provide a closer and check similar to the device disclosed in my patent No. 833,387, dated October 16, 1906, with a spring adjustable from the outside of the casing, and to so connect the spring to the spindle that the turning of the spindle in either direction compresses the spring in one direction only and also does away with the tendency to clamp the spring in one place.

In the drawings; Figure 1 is a longitudinal, vertical sectional view of a door closer and check, embodying the improvements of my invention; Fig. 2 is a view of the spindle and packing gland, the lower half of the spindle and gland being in section; Fig. 3 is a fragmentary cross section on line X—X of Fig. 5; Fig. 4 is a detail plan view of the lower half of the spindle; Fig. 5 is a plan view of the entire mechanism with the top plate and cover removed; Fig. 6 is a fragmentary plan view of the spring-adjusting device; Fig. 7 is a detail view, in elevation, of the saddle.

With the exception of the improvements hereinafter to be described, the construction and operation of this device is the same as that disclosed in my former patent No. 833,387, and, therefore, it is necessary only to describe briefly the general structure, in which 1 represents the casing having the two separate chambers 2 and 3.

4 is the spindle gland.

5 is the lower part of the spindle, rotatably mounted in the gland 4 and operatively connected to the piston 6, in the chamber 3.

7 is a valve controlling the by-pass 8 of the piston chamber.

9 is the upper part of the spindle, removably mounted in the lower part 5 and adapted to rotate the same.

10 is a shoe having a recess and adapted to

be secured in the lower edge of the door, to afford a seat therefor upon the upper part 9 of the spindle.

11 is a cover for the casing.

My invention relates more particularly to the construction set forth below, which is shown in the preferred form, but minor details may be changed without departing from the scope of my invention.

12 is an off-set portion of the upper spindle 9.

13 is a slide mounted to operate between the guides 14 in the upper chamber 2.

15—15 are cam surfaces on the slide 13.

16—16 are rollers mounted in the off-set 12 and engage the cams 15 when the spindle is rotated.

17 is a saddle comprising curved top and bottom members or plates 17^a 17^b (Fig. 15) joined by end members 17^b and 17^c (Fig. 7).

17^d 17^d are perforated ears projecting from the end member 17^c.

13^a 13^a are lugs projecting from the center of the slide 13 and carrying pins 13^b 13^b adapted to engage in the perforated ears 17^d to form a detachable bearing for the saddle 17.

18 is a post extended upward from the bottom of the chamber 2.

19 is a flanged cap rotatably mounted on said post 18, and is provided with a vertical groove 20.

21 is a coil spring one end of which engages in the groove 20 of the cap 19 and the other end is bent to engage the end members 17^b of the saddle 17 when the spring is under tension. The flanged top of the cap 19 is cut to form a ratchet 22.

23 is a pawl carried by the cover 11, adapted to engage the ratchet 22.

24 is a band encircling the spring 21 to prevent excessive expansion.

25 is a sheet metal top placed over the entire device, preventing the dirt from entering the same and presenting a flat surface at the floor level.

The operation is as follows: When the spindle 9 is rotated in either direction by the opening of the door, one of the rollers 16 in the offset portion of the spindle engages one of the cam surfaces 15 of the slide 13, thereby moving the slide and winding the spring 21 by means of the saddle 17. When the door

is released, the reaction of the spring returns it to its closed position and the piston prevents a too rapid movement thereof.

- It is often desirable, as well as necessary, 5 to adjust the tension of the spring, and this is accomplished by removing the top 25 and adjusting the ratchet 22, which, being connected to the spring 21, either adds to or decreases the tension thereof.
- 10 By the structure set forth above, the adjusting parts are always readily accessible. As the cut-away portion 26 of the saddle enables the curved top and bottom plates 17^a thereof to straddle the spring, as shown in 15 Fig. 5, the strain is evenly distributed around the post 18, and when the spring is under tension, any tendency to bind is prevented, the saddle being attached to the center of the slide, and the slide having a long bearing, 20 even movement is given to the saddle as it pulls from the center of the slide. With either right or left hand movement of the spindle the spring is wound in the same direction, and the spindle in its full movement 25 should not wind the spring more than one-quarter of a turn when in proper adjustment.

What I claim is:

1. In a door closer, the combination of a casing, a spindle, a slide mounted in the casing and operated by the spindle, a coil spring, a saddle connected to the spring and pivoted directly on the slide, and a rotatable member engaging the spring and adapted to be secured in different positions to adjust 35 the tension of the spring.
2. In a door closer, the combination with a casing, of an adjustable coil spring, a spindle, a slide operated by the spindle, a saddle detachably pivoted to one end of the slide 40 and connecting the slide to the coil spring, and a rotatable member engaging the spring

and adapted to be secured in different positions to adjust the tension of the spring.

3. In a door closer, the combination with a casing of a coil spring, a spindle, a slide operated by the spindle, a curved hollow saddle connecting the coil spring to the slide and passing above and below the coils of the spring, and a rotatable member engaging the spring and adapted to be secured in different 50 positions to adjust the tension of the spring.

4. In a door closer, the combination with a casing of a coil spring, a spindle, a slide operated by the spindle, a curved saddle frame connected to the coil spring and detachably pivoted to the center of the slide, the coils of the spring passing between the plates of the saddle frame, and a rotatable member engaging the spring and adapted to be secured in different 55 positions to adjust the tension of the spring.

5. In a door closer, the combination with a casing of an adjustable coil spring, a rotatable member engaging the spring and adapted to be secured in different positions to adjust 65 the tension of the spring, a slide, a spindle operating the slide, and a saddle pivoted to the slide comprising curved plates passing above and below the coils of the spring, said saddle detachably connected to the spring 70 and held in connection therewith by the tension thereof.

6. In a door closer, the combination with a casing, of a coil spring, a slide, a spindle to operate the slide, and a saddle pivoted to the 75 slide detachably engaged by one end of the spring and held in engagement by the tension of the spring.

WILLIAM K. HENRY.
